UNITED STATES PATENT OFFICE.

WILLIAM A. HAND, OF PROVIDENCE, RHODE ISLAND.

DESIGN FOR A LEMON-SQUEEZER.

46,339.

Specification for Design.

Patented Sept. 1, 1914.

Application filed May 27, 1914. Serial No. 841,384. Term of patent 14 years.

To all whom it may concern:

Be it known that I, WILLIAM A. HAND, a citizen of the United States, residing at Providence, in the county of Providence and State of Rhode Island, have invented a new, original, and ornamental Design for Lemon-Squeezers, of which the following is a specification, reference being had to the accompanying drawing, forming a part thereof.

Figure 1 is a perspective view of a lemon

squeezer showing my design, Fig. 2 is a similar view illustrating the same in an inverted position.

I claim:

The ornamental design for a lemon squeezer, as shown.

WILLIAM A. HAND.

Witnesses:

THOMAS F. McMAUGH,
JOHN J. KELLEY.
